DESIGN FOR A TEA-BALL

Lester W. Nerney, Attleboro, Mass.

Application May 2, 1934, Serial No. 51,671

Term of patent 3½ years

To all whom it may concern:

Be it known that I, LESTER W. NERNEY, a citizen of the United States, residing at Attleboro, in the county of Bristol and State of Massachusetts, have invented a new, original, and ornamental Design for Tea-Balls, of which the following is a specification, reference being had to the accompanying drawing, forming part thereof.

Fig. 1 is a perspective view of a tea-ball showing my new design, and

Fig. 2 is a perspective view showing the tea-ball supported from the chain with the cover open.

I claim:

The ornamental design for a tea-ball, as shown and described.

LESTER W. NERNEY.
